CLAIM

The ornamental design for a bracket for use with a welding table, as shown and described.

DESCRIPTION

FIG. 1 is a front view of a bracket for use with a welding table;

FIG. 2 is rear view thereof;

FIG. 3 is a top view thereof;

FIG. 4 is right-side view thereof;

FIG. 5 is a front perspective view thereof;

FIG. 6 is a rear perspective view thereof; and,

FIG. 7 is an enlarged view of area 7 in FIG. 1.

The broken lines in depict the boundaries of the enlarged view of FIG. 7, and thus form no part of the claimed design.

1 Claim, 7 Drawing Sheets
